United States Patent Office

Des. 216,459
Patented Jan. 13, 1970

216,459

BOTTLE

Heikki Viitanen, Turku, Finland, assignor to Farmos Oy,
Turku, Finland

Filed Jan. 27, 1969, Ser. No. 15,574

Term of patent 14 years

Int. Cl. D9—01

U.S. Cl. D9—59

FIG. 1

FIG. 3

FIG. 2

FIG. 4

FIG. 6

FIG. 5

FIG. 1 is a top plan view of a bottle, embodying my new design;

FIG. 2 is a front elevational view;

FIG. 3 is an elevational view looking from the left of FIG. 2;

FIG. 4 is an elevational view looking from the right of FIG. 2;

FIG. 5 is a bottom plan view; and

FIG. 6 is a rear elevational view on a reduced scale.

I claim:

The ornamental design for a bottle, as shown.
